DOUBLE CONE REEL

Frederick M. Littell, Chicago, Ill., assignor to
 F. J. Littell Machine Company, Chicago, Ill., a
 corporation of Illinois

Application April 20, 1951, Serial No. 221,985

10 Claims. (Cl. 242—78)

1
 The invention relates to reels for supporting coils of metal stock for rotation and has reference more particularly to double cone reels of improved construction which will have utility in rotatably supporting coils regardless of their width so that the metal strip can be uniformly withdrawn therefrom as required by various processing operations conventionally performed on such metal stock.

An early and commercially practical form of double cone reel is shown in the patent to Moxley, No. 1,990,084, granted February 5, 1935. The apparatus of this patent includes a pair of coil supporting members supported on conventional ways or guides and adapted to be moved simultaneously in directions toward and away from each other. For loading the double cone reel the coil of metal strip is rolled down a ramp onto a lifting saddle which is employed to elevate the coil for coaction with the coil supporting members. It is extremely difficult to position the heavy coil on the exact center between the coil supporting members but in the event this is not done so that the coil is located off-center, then it is necessary for the operator to bodily move the coil by using manual means of some sort or by employing one of the coil supporting members as a thrust applying means to move the coil laterally in an amount sufficient to properly center the coil. In either case the handling of the heavy coil is difficult and most unsatisfactory and severe damage very often results especially to the side edges of the strip material.

An object of the present invention resides in improved coil handling apparatus of the double cone type whereby an off-center coil can be easily and precisely recentered.

A more specific object of the invention resides in the provision of a double cone reel embodying improved centering features whereby an off-center coil can be engaged by the coil supporting members in the usual manner for rotatably supporting the coil and whereby the entire unit can then be moved laterally in either direction for precise centering of the coil.

A further object is to provide recentering structure for a double cone reel which will employ hydraulic means for laterally shifting the coil supporting members and their threaded connecting shaft as a unit, and which members at the time may have engaged relation with a coil for rotatably supporting the coil in the conventional manner.

Another object is to provide a double cone reel including coil supporting members equipped with

rollers for mounting the said coil supporting members for substantially frictionless movement on the conventional ways or guides of a supporting frame. As a result of the roller mounting for the coil supporting members it is possible to center the coil on the reel with a minimum expenditure of force and this is particularly so when the coil supporting members engage and mount a coil for rotation.

10 A further object resides in the provision of roller mounted coil supporting members which are operatively connected by a threaded shaft having a right hand threaded section in engagement with one coil supporting member and a left hand threaded section in engagement with the other coil supporting member, whereby the members may be moved toward or from each other by rotation of the shaft. Spline structure is provided at one end of the threaded shaft for coupling the shaft to driving means by which the shaft is rotated. Such spline structure is necessary for the recentering feature since the structure permits movement of the threaded shaft in axial directions under the thrust imparted thereto by an hydraulic cylinder for centering the coil.

20 Another object is to provide an improved double cone reel having a coil cushioning or protective saddle for absorbing the impact of the heavy coil when the same is rolled into position between the coil supporting members of the reel. The cushioning saddle is located on respective sides of a lifting saddle and an hydraulic cylinder is employed for elevating the cushioning saddle whereby the same is located in operative position for absorbing the initial impact of the coil as it is rolled into the reel and which can then be operated for gently depositing the coil onto the lifting saddle.

30 With these and various other objects in view, the invention may consist of certain novel features of construction and operation, as will be more fully described and particularly pointed out in the specification, drawings and claims appended thereto.

40 In the drawings which illustrate an embodiment of the device and wherein like reference characters are used to designate like parts—

50 Figure 1 is a side elevational view of a double cone reel constructed in accordance with and embodying the improved features of the present invention;

55 Figure 2 is a top plan view of the double cone reel as shown in Figure 1, this view clearly illustrating the lifting saddle and the cushioning saddle.

idle having associated relation with each other;

Figure 3 is a horizontal sectional view with the coil supporting members and saddles being removed in order to disclose the threaded operating shaft, the spline structure therefor, and the hydraulic means, all of which constitute the recentering feature of the invention;

Figure 4 is an end view showing in elevation the right hand end of the double cone reel as illustrated in Figure 1 with a second coil being shown supported on the ramp and with the operative position of the cushioning saddle being shown in dotted lines;

Figure 5 is a sectional view taken transversely of the reel approximately through the cushioning and lifting saddles in order to illustrate the construction of these parts;

Figure 6 is a detail sectional view illustrating the spline structure at one end of the threaded operating shaft;

Figure 7 is a detail sectional view illustrating the roller bearing for mounting the other end of the threaded operating shaft; and

Figure 8 is a detail sectional view showing the hardened rollers and their guides which are provided for the coil supporting members to permit substantially frictionless movement of the members on conventional ways of the supporting frame.

The coil handling apparatus selected for illustrating the present invention essentially consists of coil supporting members 10 and 11 which are supported for substantially frictionless rolling movement on conventional ways or guides of a supporting frame structure generally indicated by the numeral 12. Each coil supporting member journals a coil supporting cone 13 and 14, respectively, each cone being backed by a plate 15. The cone 13 is suitably journaled by member 10 through the instrumentality of shaft 16, the said shaft being provided with a worm, not shown, but which is located in the gear housing 17, and which gear has operative connection with similar worm gear structure contained in housing 18. The shaft 20 projects from housing 18 and the pulley 21 is suitably secured thereto. The said pulley has operative connection with motor 22 positioned within the frame of member 10 and as a result the cone 13 is driven for rotating the coil 23 of metal stock supported thereby in a paying-off direction. The base 24 for the motor is pivoted at 25 and by means of the turnbuckle connection 26 the position of the motor 22 can be varied to vary the tension on the belts 27. The idler cone 14 is journaled by member 11 through the instrumentality of shaft 28, said shaft being suitably mounted in housing 30 for free rotation.

The coil supporting members 10 and 11 are adapted to ride in an axial direction to and fro on the built-up structure previously identified by numeral 12. The frame structure may consist of spaced side plates 31 and 32, each being supported on a base member 33 which has direct contact with the foundation such as indicated by numeral 34, which may be of concrete or the like. The members 31, 32 and 33 extend for the length of the coil handling apparatus and the spaced side members, namely, 31 and 32, provide supports for conventional ways or guides 35 and 36, respectively. The rollers of the coil supporting members to be presently described in detail roll on the ways 35 and 36 for which purpose the ways are provided with hardened steel insets 37, as best shown in Figure 8. A vertical spacer or

partition 38 extends between each lower way 35 and its corresponding upper way 40, said ways being vertically spaced thereby to accommodate the hardened steel insert and a roller 41 of the coil supporting member.

As previously stated, the coil supporting members 10 and 11 are roller mounted on the ways 35 and 36 provided by the supporting frame structure. For this purpose each member is provided with depending side pieces 42 and 43 on the respective sides of the member to which the rollers 41 of the member are supported. As best shown in Figure 8, the journaling shaft for each roller, indicated by numeral 44, is provided with an enlarged head portion 45. The head portion retains the roller 41 on the shaft end which carries roller bearings 46 to insure substantially frictionless rotation. The end of shaft 44, projecting beyond the side piece 42, is suitably threaded for receiving the securing nut 47. To insure proper lubrication for the roller 41 and the roller bearing 46 the shaft 44 is provided with passages such as 48 through which lubricant may be forced in any well known manner.

In the operation of placing a coil of metal stock on the double cone reel, as herein disclosed, it is customary to move the coil supporting members so that the cones 13 and 14 will be spaced a distance greater than the width of the coil to be supported thereby. The coil is then elevated to align the center opening in the coil with the cones, and then the coil supporting members 10 and 11 are moved in a direction toward each other. This simultaneous movement of the members toward and from each other is accomplished by means of a threaded shaft indicated by numeral 50. Said shaft extends from one end of the coil handling apparatus to substantially adjacent the other end and the shaft has two threaded sections, one section 51 having right hand threads and the other section 52 having left hand threads. Structure 53, which is fixed to the coil supporting member 10, has threaded relation with section 51 of the threaded shaft. In a similar manner coil supporting member 11 has structure 54 in threaded relation with section 52 of the shaft. It will therefore be manifestly clear that as shaft 50 is rotated in one direction, the right and left hand threads on the sections respectively will cause movement of the coil supporting members and thus the cones in a direction away from each other, whereas opposite rotation of shaft 50 will effect in a similar manner movement of the members and thus the cones in a direction toward each other.

The shaft 50 is rotated by motor 55 conveniently located in the frame structure 12 between side frames 31 and 32 and at one end of the coil handling apparatus. Belts such as 56 operatively connect the motor to the pulley 57 of gear reducing mechanism such as indicated by numeral 58. A portion of such gear reducing mechanism is shown in Figure 6 and which is provided with the shaft 60 which is accordingly driven at the desired speed upon energization of motor 55. The collar 61 is suitably keyed to the supporting end of shaft 60 and said collar is provided with the flange 62 having contacting relation with a similar flange 63 on the sleeve 64. Collar 61 and sleeve 64 are connected so as to transmit rotation from the shaft to the sleeve by means of the securing bolts 65. At its opposite end the sleeve 64 is provided with a second flange 66 which is suitably connected by the securing bolts 67 to the spline collar 68. The spline collar has a re-

duced portion 70 which is threaded at its extreme end for receiving the member 71. Between the enlarged portion of the spline collar 68 and member 71 there is mounted on the spline collar a supporting part indicated by numeral 72, which part provides roller bearings 73 by means of which the spline collar is supported for substantially frictionless rotation. The fitting 74 is fixed to the part 72 and said fitting provides for proper lubrication of the roller bearing 73. As best shown in Figure 1, the part 72 is suitably mounted as at 75 on the frame structure 12 of the coil handling apparatus.

The sleeve 64 and spline collar 68 provide tubular structure for receiving the spline section 76 of the threaded shaft 50. Said spline section 76 consists of a plurality of alternating grooves and projections which interfit with similar structure provided by the collar 68. It will accordingly be understood that rotation of collar 68 is imparted to shaft 50 through the spline connection and that it is likewise possible to move shaft 50 in an axial direction to an extent as permitted by the spline connection. Sleeve 64 has a length approximately equal to the length of the spline section 76 and the structure accordingly permits axial movement of shaft 50 for a length equal to that of the spline section and which may vary from six inches to one foot, depending on the size of the coil handling apparatus.

At its other end the threaded shaft 50 is journalled for rotation, as best shown in Figure 1. The shaft is reduced at this end to provide portions 77 and 78, the latter portion mounting the ball bearing assembly indicated in its entirety by numeral 80. The housing 81 is provided for said ball bearing assembly and following assembly of the parts within the housing its open end is closed by cover 82 suitably secured to the housing by bolts 83. The securing nut 84 is threaded to the end of shaft 50 so as to hold the ball bearing assembly in place on the shaft and the nut is in turn locked by the cotter pin 85. The piston rod 86 extends from the right end of the housing 81, being threadedly secured to the housing as at 87 and suitably locked in said threaded relation by nut 88. The piston rod accordingly constitutes a rear extension as regards housing 81 and for all practical purposes may be an integral part of the housing. Since the threaded shaft 50, housing 81 and piston rod 86 all move in a lateral direction as a unit it is desirable to provide some form of guiding means which may be easily provided to maintain movement of the shaft, housing and piston rod in a true axial direction. In accordance with the invention, an indicating scale 91 is secured to the guiding structure 90 so as to extend laterally to adjacent the right hand end of the coil handling apparatus. By suitable calibration of the scale 91 the same can be employed to visually indicate the off-center position of the coil and therefore the amount of lateral movement necessary for re-centering the coil.

The numeral 92 indicates the hydraulic cylinder which supplies the necessary power for re-centering the coil of stock. The right hand end of the cylinder is suitably secured to the frame structure 12 by a clevis connection such as 93 and the piston rod 86 projects from the other end of the cylinder to operatively connect with the housing 81 and the threaded shaft 50. Numerals 94 and 95 indicate the piping connections to the hydraulic cylinder 92 which are necessary for admitting and exhausting a pressure fluid whereby to effect movement of the piston rod 86 in lateral

directions toward the right or left, as viewed in Figures 1, 2 and 3. When it is desired to place a coil of stock on the double cone reel of the invention the cones 13 and 14 are moved apart by rotation of the threaded shaft 50 which effects movement in a direction away from each other of members 10 and 11. The coil is then rolled between the cones 13 and 14, being supported on a lifting saddle to be presently described in detail.

10 The saddle is employed to elevate the coil until

the opening in the same is substantially aligned with the cones, whereupon the threaded shaft 50

is rotated in an opposite direction to effect move-

ment of the supporting members toward each

other.

It will be assumed for purposes of this discus-

sion that the coil is off-center, say, for example, in a direction toward the left. As a result cone 13

will contact the coil before cone 14. However, no

harm is done to the coil due to initial contact

therewith of cone 13, since it will be understood

that the entire unit, including the supporting

members 10 and 11 and their threaded connecting

shaft 50, constitutes a floating unit during this

20 operation. The ports 94 and 95 of the hydraulic

cylinder 92 are open during this operation of the

coil so as not to interfere with lateral movement

of threaded shaft 50, which is accordingly free to

move in a direction toward the left. Movement

25 of the threaded shaft 50 and cone 14 in a direc-

tion toward the left necessarily results from con-

tinued rotation of the threaded shaft following

initial contact of cone 13 with the coil. Presently

30 both cones will have the desired contacting en-

gagement with the coil for rotatably supporting

the coil in the conventional manner as well under-

stood in the art of double cone reels. Although

the coil is now properly supported for rotation by

the cones, nevertheless the coil is off-center. For

35 re-centering the coil the entire unitary assembly

including the coil, the cones having engaged re-

lation therewith, the members 10 and 11, and

their threaded connecting shaft 50, are all moved

laterally in a direction toward the right by force

40 applied in this direction by hydraulic cylinder 92.

For this purpose port 95 is open and a pressure

fluid such as oil is admitted to port 94. The action

of the high pressure oil on the piston (not shown)

within cylinder 92 will accordingly impart move-

50 ment to piston rod 86 and to the unitary assembly

of the parts as described. When the coil has

reached the desired center position as indicated

by the scale 91, the pressure fluid to cylinder 92 is

55 terminated and the coil will remain in centered

position unless the unitary assembly is moved by

further energization of the hydraulic cylinder 92.

The double cone reel as herein disclosed in-

60 cludes a lifting saddle indicated by numeral 97,

Figures 2, 4 and 5. The saddle is supported and

mounted for movement in vertical directions by

means of box guide 98. The box guide 98 is sub-

stantially rectangular in plan, as will be clearly

65 evident from Figure 3, the same having portions

on all four sides and which in turn have guiding

66 movement in the box frame 100. The box frame

is suitably supported by the frame structure 12,

being located substantially centrally of the length

of the structure and having its lowermost portion

extending through the frame structure so as to

70 depend into the well 101 provided therefor by the

foundation 34 of the reel. It will be observed

75 from Figure 3 that the box frame is substantially

rectangular in plan so as to encompass the box

guide. It will be clearly evident that the threaded

shaft 50 extends through the box frame 100 and

the box guide 98 and in order to accommodate the said shaft and permit vertical movements of the box guide the opposing side walls of the same are provided with vertical slots 102. Also it will be observed that the piston rod 103 and the hydraulic cylinder 104 are offset so as not to interfere with the threaded shaft 50. The piston rod 103 is secured at its upper end as at 105 to the lifting saddle 97. The cylinder 104 at the opposite end of the structure is pivoted at 106 to the base member 107 which is suitably fixed to and supported from the box frame 100. Piping such as 108 and 109 connects with the hydraulic cylinder 104 to form ports for the cylinder and through which pressure fluid is either supplied or exhausted to effect movement of piston rod 103 whereby to elevate or lower the saddle 97.

In Figure 4, an extra coil, indicated by numeral 23a, is shown in dotted lines supported on the ramp 110 and held against rolling movement by the latch 111. When coil 23 has been used up and it is desired to locate coil 23a on the double cone reel the latch 111 is withdrawn and the coil is allowed to roll down the ramp to take its position between the coil supporting members 10 and 11 which have been moved apart to accommodate the coil. The present invention provides a protective saddle or a cushioning saddle 112 for the purpose of absorbing the initial impact of the rolling coil as the same leaves the ramp and to gently ease the coil onto its lifting saddle 97 so as to eliminate the possibility of any damage being done to the coil in this initial loading operation of the same. The cushioning saddle 112 is pivoted to the frame structure by the pivot pin 113 and said structure is preferably rectangular so as to have encompassing relation with the lifting saddle, all as clearly shown in Figure 2. The top surface of the saddle may be equipped with rubber pads 114 as an additional protective measure against damage to the coil of metal stock. The power cylinder for controlling the elevating and lowering movements of the cushioning saddle is indicated by numeral 115, the cylinder being pivoted in a conventional manner at 116 to plates 117 forming part of the frame structure. The piston rod 118 extending from the opposite end of the cylinder is pivoted in any suitable manner as at 120 to the cushioning saddle. Piping 121 and 122 is shown as having connection with the cylinder at the respective ends of the same whereby to provide ports for the pressure fluid supplied and exhausted therefrom. Before latch 111 is removed to release coil 23a the cushioning saddle 112 is elevated by operation of cylinder 115 to position the saddle as shown in dotted lines, Figure 4. The coil 23a will roll onto the elevated saddle which will cushion its impact and thus prevent damage to the metal of the coil. The cushioning saddle also operates to prevent bouncing back and forth of the coil, which action would otherwise take place were it not for the saddle. The next operation is to lower the cushioning saddle 112 which gently deposits the coil onto the lifting saddle 97.

The spline structure at one end of the threaded shaft 50 and the power cylinder at the opposite end of said threaded shaft constitute essential features in connection with recentering of the coil. Since the shaft 50 is movable in lateral directions to an extent as permitted by the spline structure, it necessarily follows that the coil supporting members 10 and 11 are likewise movable and for this reason the invention provides rollers for the coil supporting members having substan-

tially frictionless mounting on their stud shafts and which roll on hardened steel inserts. Were it not for this roller mounting of the coil supporting members it would be extremely difficult to 5 properly re-center a coil, owing to the tremendous force which would be required to move the unitary assembly. The hydraulic cylinder 92 is entirely satisfactory for supplying the desired force required for re-centering the coil when the members are roller mounted as herein described. In 10 rolling the coil down the ramp and onto the reel due caution must be observed to maintain the coil approximately centered as regards the reel. It very seldom happens that the coil is located off center more than six or eight inches. Therefore 15 the coil re-centering structure of this invention is entirely satisfactory for all practical purposes. It is further necessary to reasonably control the speed with which the coil enters the reel. The 20 cushioning saddle 112 will absorb considerable impact such as may be initially applied and by absorbing the same the coil is prevented from rocking back and forth. Release of the hydraulic pressure in cylinder 115 will deposit the coil onto 25 the lifting saddle 97 which is then actuated to elevate the coil so as to align the openings in the same with the cones which are then moved toward each other to rotatably mount the coil and which 30 may be positively driven by cone 13 to pay out the strip material in the usual manner.

The invention is not to be limited to or by details of construction of the particular embodiment thereof illustrated by the drawings, as various other forms of the device will of course be apparent to those skilled in the art without departing from the spirit of the invention or the scope of the claims.

1. In coil handling apparatus, a longitudinal frame, a pair of coil supporting members mounted on said frame for movement toward and from each other, a shaft extending lengthwise of the frame and having a section at one end provided with right hand threads and a section at the other end provided with left hand threads, one 40 coil supporting member having connection with the right hand threaded section and the other coil supporting member having connection with the left hand threaded section, driving means for rotating the shaft operatively connecting with one end of the shaft through a spline connection whereby to permit lengthwise movement of the shaft, and power means at the opposite end of the shaft for moving the same lengthwise.

2. Coil handling apparatus as defined by claim 55 1, additionally including rollers journalled by each coil supporting member whereby the member has rolling movement on the frame, hardened steel inserts provided by the frame on which said rollers are adapted to roll, and wherein the driving means for rotating the threaded shaft comprises an electric motor and the power means for moving the threaded shaft lengthwise comprises a pressure cylinder.

3. In coil handling apparatus, a longitudinal frame including spaced guideways, a pair of coil supporting members mounted on said spaced guideways for movement toward and from each other, a threaded shaft located substantially centrally between the spaced guideways and extending lengthwise of the frame, said threaded shaft having right hand threads at one end and left hand threads at its other end, means provided by each coil supporting member having threaded connection with the shaft respectively, whereby 60 rotation of the threaded shaft in one direction 70 75

effects movement of the coil supporting members away from each other and rotation of the shaft in an opposite direction effects movement of the members toward each other, driving means for rotating the shaft in either direction, spline structure at one end of the shaft operatively connecting the shaft to said driving means whereby to permit lengthwise movement of the shaft while maintaining operative connection therewith for rotating the same, and a pressure cylinder connecting with the shaft at its opposite end for effecting movement of the shaft and the connected coil supporting members in directions lengthwise of the frame.

4. Coil handling apparatus as defined by claim 3, additionally including rollers journaled by each coil supporting member for roller mounting the member on the spaced guideways of the frame, hardened steel inserts provided by said frame on which said rollers are adapted to roll, and wherein said driving means for rotating the shaft comprises an electric motor.

5. In a double cone reel, the combination including longitudinal frame structure, a pair of coil supporting members mounted on the frame for rolling movement toward and from each other, means for effecting such movement of the coil supporting members including a threaded shaft extending lengthwise of the frame, said shaft having a right hand threaded section in threaded engagement with one coil supporting member and having a left hand threaded section in threaded engagement with the other coil supporting member, driving means for rotating the shaft in either direction and having operative connection therewith at one end, and means for centering a coil supported by said coil supporting members comprising a spline connection at said end of the shaft interposed between the same and the driving means therefor, whereby to permit lengthwise movement of the unitary assembly including the shaft, coil supporting members and coil, and power means having connection with the shaft at its opposite end for effecting movement of the unitary assembly in directions lengthwise of the frame.

6. A double cone reel as defined by claim 5, additionally including coil supporting cones journaled for rotation by the coil supporting members respectively, and driving means carried by one of said coil supporting members for rotating its cone whereby to produce rotation of the coil when rotatably supported by the cones.

7. In a device for rotatably supporting and centering a coil of strip material, the combination of a bed frame, coil supporting members movable along the frame, coil supporting cones journaled by the supporting members, screw shaft means extending lengthwise of the bed frame and having right and left hand threaded sections in threaded engagement with the coil supporting members respectively, means for rotating the screw shaft means to simultaneously move said coil supporting members toward or away from each other, whereby the coil supporting cones are caused to engage and rotatably support a coil, and means for centering the coil including spline structure in operative association with the screw shaft means and interposed between the screw shaft means and the means for rotating the same, whereby to permit lengthwise movement with respect to the frame of the

unitary assembly including the screw shaft means, the coil supporting members in threaded connection therewith and the coil rotatably supported thereby.

5 8. A device for rotatably supporting and centering a coil of strip material as defined by claim 7, additionally including power means fixed to the bed frame and operative to effect lengthwise movement of the unitary assembly for centering purposes.

10 9. In coil handling apparatus, the combination with a frame, of a pair of coil supporting means mounted on the frame for horizontal movement in directions longitudinally of the frame, a coil lifting saddle positioned centrally between the coil supporting means and mounted for vertical movement transversely of the longitudinal axis of the frame, means for moving the coil lifting saddle vertically in an upward direction whereby to elevate a coil supported by the saddle and align the coil with said coil supporting means, a cushioning saddle disposed in adjacent relation with the coil lifting saddle, means pivotally securing the cushioning saddle to the frame at one side of the frame to provide a pivot axis for the cushioning saddle which is parallel to the longitudinal axis of the frame but displaced laterally of the center of the frame, and other means separate and independent from said first mentioned means and located adjacent the frame on the side opposite said pivot axis for effecting pivotal movement of said cushioning saddle, whereby the cushioning saddle may be located in an elevated operative position or in a lowered inoperative position.

15 10. In coil handling apparatus, the combination with a frame, of a pair of coil supporting means mounted on the frame for horizontal movement in directions longitudinally of the frame, a coil lifting saddle positioned substantially centrally between the coil supporting means and mounted for vertical movement transversely of the longitudinal axis of the frame, means for moving the coil lifting saddle vertically in an upward direction whereby to elevate a coil supported by the saddle and align the coil with said coil supporting means, a cushioning saddle in the form of an open rectangular frame disposed in adjacent relation with the lifting saddle and with the lifting saddle located within the rectangular opening of the frame, means pivotally securing the cushioning saddle to the frame of the coil handling apparatus at one side of the frame to provide a pivot axis for the cushioning saddle which is parallel with the longitudinal axis of the frame but displaced laterally of the center of the frame, and a pressure cylinder located adjacent the frame on the side opposite said pivot axis for effecting pivotal movement of the cushioning saddle, whereby the cushioning saddle may be located in an elevated operative position or in a lowered inoperative position.
